[57] CLAIM

The ornamental design for a hat holder stand for an individual hat, as shown and described.

DESCRIPTION

FIG. 1 is an elevated perspective view of a hat holder stand for an individual hat showing my new design;

FIG. 2 is an enlarged top plan view thereof;

FIG. 3 is a side elevational view of FIG. 2, the opposite side being a mirror image;

FIG. 4 is a front elevational view of FIG. 2, the rear view being substantially the same except for the more downwardly sloping curvature of the hat form element; and,

FIG. 5 is a bottom plan view of FIG. 2.
